PRINTING TELEGRAPH SYSTEM

Harry O. Rugh, Chicago, Ill., assignor to Automatic Electric Laboratories, Inc., Chicago, Ill., a corporation of Delaware

Application May 21, 1945, Serial No. 594,833

7 Claims. (Cl. 179—2.5)

1

The present invention relates to printing telegraph systems and, more particularly, to improvements in the methods and apparatus for transmitting and receiving coded signals over standard commercial power lines.

In the Harry O. Rugh Patent No. 2,290,385, granted July 21, 1942, there is disclosed a printing telegraph system having a transmitting station, a receiving station, and an interconnecting line over which coded signals are transmitted to control the receiving station printer. That patent is concerned more particularly with the mechanical structure of the sending and receiving apparatus. The present invention, however, deals with the use of the mechanical transmitter and receiver apparatus disclosed in the above-mentioned patent in a system in which a commercial power line is utilized as a carrier channel in the transmission and reception of signals in either direction.

It is an object of the present invention to provide in a system of the character described an improved transmitting unit for producing carrier current having a frequency of oscillation above the audible range and modulating such oscillations, by means of an audio frequency oscillator and a sender, in accordance with a telegraphic code.

It is another object of the invention to provide in a system of the character described an improved receiving unit for receiving and demodulating the received modulated carrier wave in order to control a printer unit in accordance with the received signals.

It is a further object of the present invention to provide in a system of the character described a combined transmitting and receiving unit whereby the apparatus, provided at any one of the stations of the system, may be utilized either as a transmitter or as a receiver.

It is a still further object to provide an economical and efficient arrangement for converting the combined transmitting and receiving unit so that it may be selectively operated as a transmitter or as a receiver.

It is a still further object of the present invention to provide in a system of the character described a new and improved arrangement for scrambling the coded signals of a message as they are being transmitted and for automatically unscrambling the transmitted coded signals as they are received, whereby the telegraphic printer at the receiving station may be operated to correctly print the coded signals of the transmitted message.

In accordance with another object of the inven-

2

tion different scrambling or transposing devices may be provided between the selecting bar contacts and the sending commutator of the sender at the transmitting station, whereby the transmitted code signals may be scrambled at will in accordance with different patterns by merely substituting different transposing devices.

In accordance with still another object of the invention different unscrambling or transposing devices may be provided between the printer control magnets and the receiving commutator at the receiving station, whereby the received scrambled code signals may be unscrambled as they are received in order to control the printer to correctly print the transmitted message.

The invention, both as to its organization and method of operation, together with further objects and advantages thereof, will best be understood by reference to the specification taken in connection with the accompanying drawings in which Figs. 1 and 2 illustrate the circuit arrangement of an improved system having incorporated therein the features of the invention briefly referred to above.

Referring now more particularly to Figs. 1 and 2 of the drawings, the improved system there illustrated comprises, in general, an east station (Fig. 1) and a west station (Fig. 2) which are interconnected by a commercial power line 10. The power line 10 also constitutes the source of operating current for the stations of the system and may, for example, be of either 110 volt alternating or direct current type.

The apparatus and circuits provided at the east and west stations are identical and, accordingly, like reference numerals, distinguished only by the letters "e" and "w," have been used to identify corresponding apparatus and circuit elements.

These stations respectively comprise sound translating devices 3e and 3w, each of which serves as a microphone and as a loudspeaker, combined carrier current oscillator-detector networks 20e and 20w, combined audio oscillator-amplifier networks 30e and 30w, power rectifier units 60e and 60w, key operated transmitter units 50e and 50w, tape printer units 60e and 60w, and printer controller amplifier networks 70e and 70w. For the purpose of rendering the respective stations active for either transmission or reception of voice and printing telegraph signals, switch keys 4e and 4w are provided. There are also provided at each of the stations, respectively, transmit and receive keys 5e and 5w having three positions for controlling the respective stations for transmission or reception of signals over the power line 10.

The oscillator-detector unit 20e provided at the east station comprises a vacuum tube 21e of the type and construction identified commercially as the type 25A6, inductance coils 22e and 23e which are inductively coupled to a pickup inductance coil 24e, a variable tuning condenser 25e, a blocking condenser 26e having a low impedance to carrier frequencies and a high impedance to audio frequencies, and a grid biasing network including the resistor 27e shunted by a by-pass condenser 28e for maintaining correct operating potential upon the control grid of the vacuum tube 21e. In this unit the condenser 25e and the inductances 22e and 23e comprise a circuit electrically tuned to give oscillations of the desired frequency of, for example, 60 kilocycles. Since the oscillator-detector 20e when operating as an oscillator functions in substantially the same manner as is described in the Hartley Patent No. 1,356,763 granted October 26, 1920, and is well known in the art, it is not deemed necessary to again describe the detailed operation thereof.

The amplifier 30e provided at the east station comprises the amplifying stages 31e and 32e which respectively include vacuum tubes 33e and 34e. The amplifier tube 33e is of the commercial 6J7 pentode type and includes input electrodes 35e and 36e, the former electrode being connected to the shielded conductor 37e, and output electrodes 38e and 39e which are coupled to the input electrode 39e of the second amplifier tube 34e through the resistance-capacitance coupling network, comprising a coupling resistor 42e and the direct current blocking condenser 43e. The correct operating potential is maintained upon the cathode 36e of the tube 33e through the provision of a cathode biasing network including a resistor 44e shunted by a by-pass condenser 45e.

The vacuum tube 34e included in the amplifier 30e is a twin triode direct-coupled power amplifier of the commercial 25N6 type having one triode, the driver, directly connected to the second, or output, triode. The input triode plate electrode 40e of the tube 34e is connected to the conductor 47e extending to the power rectifier unit 80e and to one terminal of the primary winding of the output transformer 48e. The output triode plate electrode 46e of the tube 34e is connected to the other terminal of the primary winding of the transformer 48e and to the conductor 49e, and is by-passed for high audio frequencies by a condenser 44e.

For the purpose of supplying positive screen and anode potentials to the screen and anode electrodes of the tubes 21e, 33e and 34e, a power rectifier, indicated at 80e, is provided. This rectifier comprises a half-wave, high-vacuum rectifying tube 81e which is commercially known as the 25Z6 type and is designed to supply direct current power from an alternating or direct current power line. More specifically, the ungrounded conductor 10a of the power line 10 is connected by way of the blocking radio frequency choke coil 82e to the plate electrodes of the tube 81e, and, in multiple therewith, is serially connected by way of the filaments of the tube 81e, the ballast resistor 83e which is partially shunted by a signal lamp 84e, the two filaments of the tube 34e in parallel, the filament of the tube 21e, and the filament of the tube 33e, to the grounded conductor 10b of the power line 10 by way of the contacts of the switch key 4e. It should be understood that the ground symbols indicated on the drawings merely indicate that such con-

nctions are soldered to the chassis mounting the apparatus disclosed, and the circuits including these grounded symbols are not completed until the switch key 4e is actuated to connect the chassis to the grounded conductor 10b of the power line 10. Accordingly, the above traced circuit provides the necessary current supply for the filaments of the various tubes provided at the east station.

The cathodes of the rectifier tube 81e are connected in multiple, through a filter network 85e which includes a series connected iron core choke coil 86e and a pair of shunt connected filter condensers 87e and 88e, to the conductor 47e. The conductor 47e is connected directly to the plate electrode 40e of the driver section of the amplifier tube 34e and is also connected to the output triode plate electrode 46e of this tube through the primary winding of the output transformer 48e. Similarly, the required positive potential is impressed upon the anode electrode 38e of the amplifier tube 33e through the plate load resistor 89e. This circuit is also provided with a condenser 41e for by-passing carrier currents which might appear across the output of the tube 33e. Positive operating potential is supplied to the screen electrode of the amplifier tube 33e through the current limiting resistor 90e which is bypassed for alternating currents by a condenser 91e.

The secondary winding of the output transformer 48e is connected by way of the normally closed contacts 108e of the key 5e to the sound translating device 3e, so that voice reception may be utilized in a manner to be described hereinafter. It should also be noted that the jack 92e and the plug 93e are provided to interconnect the tape printer unit 60e and the schematically illustrated amplifier unit 70e in series with the secondary winding of the output transformer 48e and the sound translating device 3e. With this arrangement the east station tape printer 60e may be controlled to record messages transmitted over the power line 10 by the west station, in a manner to be described hereinafter.

Referring now to the telegraph transmitter unit 50e, attention is directed to the fact that this unit is disclosed in detail in the above-mentioned Rugh patent. Briefly considered, the transmitter comprises a plurality of keys 51e arranged to be actuated by an operator to complete circuits through the select bars 52e (I-V) in accordance with a prearranged code. When a key, such as 51e, is actuated, certain of the select bars 52e (I-V) are energized and, at the same time the insulated trip lever 53e is rotated slightly in a clockwise direction and withdraws the catch member 54e from the distributor arm 55e. When this occurs the distributor arm 55e is driven a single revolution in the direction indicated, by a motor not shown, over the contacts 56e (I-V), certain ones of which are marked by the actuated key 51e and the associated select bars 52e in accordance with the code of a particular letter or digit to be transmitted. It will be noted that when the distributor arm 55e rotates a slight distance, it engages the start contact 57e thereby to complete a circuit including the control conductors 57e and 58e. Accordingly, each time the distributor arm 55e engages the start contact 57e or a marked one of the contacts 56e (I-V), circuits are completed between the control conductors 57e and 58e to cause the amplifier 30e to oscillate at an audible frequency, for example, 400 cycles per second, and to modulate the 60

kilocycle carrier wave generated by the oscillator 20e in accordance with the particular code of the letter or digit to be transmitted. A detachable transposing plug 59e is also provided in order to scramble the signals of the prearranged code of each of the operated keys 51e. Referring to the drawings, it will be noted that the AIII terminal of the plug 59e is connected to the BV terminal thereof, and that the AIV and AV terminals are connected, respectively, to the BIII and BIV terminals. It will be understood that many other combinations may be utilized to scramble the coded signals by interchanging differently jumpered detachable transposing plugs, such as 59e, in the circuit extending between the select bars 52e (I-V) and the contacts 56e (I-V).

The east station may be coupled to the power line 10 by way of an inductance-capacitance network 6e, comprising the inductances 7e and 8e and the condensers 11e and 12e, and the variable coupling condenser 3e, one branch of this circuit extending by way of the variable volume control 13e and the other branch extending by way of the contacts 104e or 105e of the key 5e to the pickup coil 24e of the oscillator-detector unit 21e.

In considering the operation of the system, it may be assumed that the operator at the east station has actuated the key 4e, thereby to condition the oscillator 20e, the amplifier 30e, and the power rectifier 80e for operation. It will also be assumed that the operator has actuated the key 5e to its locking transmit position, thereby to close the contacts 104e, 105e, 107e and 108e and to open the contacts 103e and 106e. As a result of the actuation of the key 4e the signal lamp 84e is illuminated to indicate to the operator that the circuits at the east station are in condition for either transmission or reception of coded signals. As a further result of the actuation of the key 4e the previously traced filament circuit is completed for the tubes 21e, 33e and 34e and the power rectifier functions to supply the necessary positive operating voltage to the screen and anode electrodes of the tubes 33e and 34e.

When the contacts 104e are closed, as a result of the actuation of the key 5e to its locking transmit position, the positive voltage which is applied to the conductor 47e by the power rectifier 80e and extending by way of the primary winding of the output transformer 48e to the plate electrode 48e of the tube 34e, is now further extended by way of the conductor 49e, the contacts 104e and the inductance 23e to the screen grid and plate electrode of the tube 21e. The oscillator 20e now oscillates at a frequency which is dependent upon the values of the condenser 25e and the inductances 22e and 23e. It will be assumed that the circuit values are such that the oscillator produces a carrier wave having a frequency of 60 kilocycles per second. Accordingly, the carrier wave is transmitted over the power line 10 by way of the inductively coupled pickup coil 24e, the contacts 105e, the variable condenser 9e, and the network 8e.

As a further result of the actuation of the key 5e at the contacts 107e a circuit is completed for connecting the translating device 3e to the secondary winding 15e of the transformer 16e. At the contacts 108e a circuit is also completed from ground by way of the primary winding 17e of the transformer 16e which is shunted by the resistance 18e, the contacts 108e, and the shielded

conductor 31e to the control grid 35e of the first amplifier tube 33e.

With the system in the condition described above, if the operator at the east station speaks into the translating device 3e, a signal voltage is developed across the low impedance primary winding 15e of the coupling transformer 16e. This voltage is reproduced across the secondary winding 17e of the coupling transformer 16e and is impressed between the input electrodes 35e and 36e of the first amplifier tube 33e. When amplified by the tube 33e, the signal voltage is impressed through the resistance-capacitance coupling network to the input control grid of the tube 34e. When amplified by the twin triode direct-coupled power amplifier tube 34e the signal voltage is impressed by way of the conductor 49e, the contacts 104e and the inductance 23e to the screen grid and plate electrodes of the tube 21e. The audio signal voltage impressed in this circuit modulates the carrier signal produced by the oscillator 20e. The modulated carrier signal is now induced into the pickup inductance coil 24e and transmitted over the power line 10 to the west station where the signal is demodulated and reproduced by the translating device 3w as will be subsequently described in connection with the operation of the east station.

From the foregoing description of the operation of the apparatus and circuits at the east station, it will be understood that the carrier wave produced by the oscillator 20e is modulated in accordance with the audio signals produced by the translating device 3e and amplified by the amplifier 30e.

Referring again to the circuit for impressing the positive operating potential upon the conductor 49e, it will be noted that in addition to extending to the anode and screen grid electrodes of the oscillator tube 21e, this circuit also extends by way of the conductor 58e to the distributor arm 55e of the transmitter 50e. Furthermore, the key 51e is connected by way of the conductor 57e, the condenser 19e and the shielded conductor 37e to the control grid 35e of the amplifier tube 33e. Accordingly, it will be understood that when a circuit is completed between the conductors 57e and 58e as a result of the actuation of the key 51e of the transmitter 50e, the output of the amplifier 30e is thereby coupled to the input of the amplifier 30e to complete a regenerative connection for the amplifier 30e. This regenerative circuit causes the amplifier to act as an audio frequency oscillator whose output appears across the primary winding of the transformer 48e. Since the secondary winding of the transformer 48e is open the primary winding acts as a plate load impedance for the output section of the tube 34e. Attention is directed to the fact that the impedance of the primary winding of the transformer 48e is common to the output section of the tube 34e and to the plate supply circuit for the carrier oscillator 20e and thereby causes modulation of the carrier wave, at the audio frequency of the amplifier 30e. The frequency of oscillation of the amplifier 30e, when it operates as an oscillator, is determined by the circuit constants of the elements included in the amplifier 30e. It will be assumed that these constants are such that the amplifier 30e oscillates at an audio frequency of 400 cycles per second. It should also be understood that the audio voltage superimposed upon the positive voltage applied to the conductor 49e causes the carrier wave produced

7 by the oscillator tube 21e to be amplitude-modulated at four hundred cycles per second.

From the foregoing description it should be understood that each time a key, such as 51e, is actuated by the operator, the distributor arm 55e makes one complete revolution and, depending upon the markings on the associated contacts 56e by the particular select bars 52e, the amplifier 30e is controlled over the conductors 51e and 58e to oscillate in the above described manner. Accordingly, the steady 60 kilocycle carrier wave transmitted by the oscillator 20e may be modulated by the 400 cycle audio frequency of the amplifier 30e each time the distributor arm 55e engages the start contact 71e or a contact marked by the select bars 52e.

When the operator at the east station has completed transmission of the desired message by the manipulation of the keys 51e of the transmitter 50e, the three-way key 5e may be restored to its neutral or receive position. Accordingly, when the contacts 104e are opened the positive potential applied to the conductor 49e is disconnected from the oscillator 20e, and, when the contacts 105e are opened the volume control 13e is included between the pickup coil 24e of the oscillator 20e and the inductance-capacitance network 6e. At the contacts 107e, the sound translating device 3e is disconnected from the primary winding 15e of the transformer 16e, and, at the contacts 108e, the secondary winding 17e of the transformer 16e is disconnected from the control grid electrode 35e.

When the contacts 103e of the key 5e are closed, a circuit is completed for extending the positive voltage applied to the conductor 47e by way of the resistor 29e, the contacts 103e, and the inductance 23e to the plate and screen grid electrodes of the oscillator tube 21e. The plate voltage of the tube 21e has now been reduced substantially by the resistance 29e included in this circuit and prevents the oscillator 20e from oscillating in the previously described manner. Accordingly, the tube 21e will now function as a detector in order to detect modulated carrier waves transmitted over the power line 10 by another station of the system. At the contacts 106e, a circuit is completed for connecting the sound translating device 3e to the secondary winding of the output transformer 48e of the amplifier 30e, whereby voice signals transmitted over the power line may be reproduced by the translating device 3e.

In order to describe the operation of the system when the key 5e is in its neutral position, it will be assumed that a 60 kilocycle carrier wave is transmitted by the west station of Fig. 2, and it will further be assumed that the carrier signal is modulated by the sound translating device 3w in accordance with sound waves received thereby. Accordingly, this modulated carrier wave is received at the east station of Fig. 1 by way of the network 6e, the variable condenser 9e, the volume control 13e, and the pickup coil 24e. This signal is detected by the tube 21e due to the inductive coupling of the inductance windings 24e and 22e. The modulation components of the received signals are detected by the tube 21e and appear across the plate load resistor 29e. The audio voltages developed thereacross are impressed upon the control grid electrode 35e of the amplifier 30e over a circuit which includes the condenser 19e and the shielded conductor 37e. The audio signal components of the modulated carrier signal are thus impressed upon the above traced circuit and

are amplified in the previously described manner by the amplifier 30e. The amplified signals in turn are impressed upon the primary winding of the output transformer 48e and, by means of the inductively coupled secondary winding of the transformer, are induced into the circuit including the sound translating device 3e. Accordingly, any audio signals transmitted over the power line through the medium of the 60 kilocycle carrier wave will be reproduced by the sound translating device 3e at the east substation.

If the subscriber at the east station desires to receive printing telegraph signals transmitted over the power line 10, the plug 93e is inserted into the jack 92e thereby to connect the schematically illustrated amplifier 70e in series with the sound translating device 3e. Attention is directed to the fact that the primary winding of the input transformer of the amplifier 70e should be substantially equal to the impedance of the sound translating device 3e in order that the signal received in the secondary winding of the output transformer 48e may be reproduced with equal amplitude by the sound translating device 3e and the input transformer of the amplifier-rectifier 70e.

It will now be assumed that the operator at the west station of Fig. 2 has manipulated the keys of the transmitter 50w to transmit printing telegraph signals over the power line 10 in substantially the same manner as has been described in connection with the operation of the transmitter 50e at the east station. When such signals are received at the east station the tube 21e functions to detect the signals and the amplifier 30e functions to amplify the signals, as has been described above. The signals amplified in the above manner are further amplified by the amplifier 70e which also rectifies the signals to control the operation and release of the relay 61e of the printer 60e in accordance with the coded signals. It will be recalled that a start signal is transmitted by the transmitter each time the distributor arm 55e or 55w is moved off normal. This signal precedes the signals transmitted in accordance with the coded signals of the letter and causes the relay 61e to operate and withdraw the catch member 62e from the distributor arm 63e. The arm 63e is frictionally engaging a continuously rotating shaft and starts rotating in the indicated direction as soon as the catch member 62e is withdrawn. When the arm 63e engages the contacts 64e (I) the relay 61e may or may not be operated, depending upon the code pulses of the letter or digit being transmitted by the operator at the west station. It will be assumed, however, that when the arm 63e is in engagement with the contact 64e (I), the arm 55w is also in engagement with the contact 56w (I) at the transmitter 50w, and that this contact is marked by the key 51w. Accordingly, the carrier wave received at the east station will be modulated by the 400 cycle audio frequency to cause the relay 61e to reoperate. Upon reoperating, the catch member 62e actuates the contacts 65e to complete a circuit which may be traced from battery, by way of the contacts 65e, the arm 63e, the contacts 64e (I), the BI and the AI terminals of the transposing plug 69e, and the relay 66e (I) to ground. From the foregoing description it should be understood that as the arm 55w of the transmitter 50w rotates over the successive contacts 56w (I-V), the arm 63e of the pointer 60e will successively engage the corresponding contact 64e (I-V) in synchronism therewith. Accordingly, the relays 66e (I-V) are

operated in combinations depending upon the markings placed by the select bars 52w upon the contacts 56w (I—V). Depending upon the combination of the relays 66e (I—V) operated during a single revolution of the arm 63e, the printer 60e is controlled in the manner described in detail in the above mentioned Rugh patent to print the letter or digit corresponding to the particular key actuated at the transmitter 50w.

After the operator at the east station has received the complete message transmitted by the operator at the west station, the operator thereat may desire to signal the operator at the west station to indicate that he desires to answer the message transmitted therefrom. In order for the operator at the east station to transmit an "attention" signal, the key 5e may be momentarily actuated to its non-locking transmit position. When the key 5e is actuated to this position, the contacts 101e are closed to connect the pickup coil 24e to the power line 10 over a circuit which is independent of the volume control 13e. When the contacts 102e are closed the positive potential applied to the conductor 49e is connected by way of the inductance 23e to the plate and screen grid electrodes of the tube 21e. Attention is directed to the fact that this circuit is substantially the same as the circuit previously traced, including the contacts 104e of the key 5e, and, accordingly, the oscillator 20e functions in the previously described manner to oscillate at 60 kilocycles per second. It will also be noted that the conductors 51e and 58e extending to the transmitter 50e are shunted by a circuit including the contacts 102e and 103e of the key 5e.

As a result of the above described actuation of the key 5e to its non-locking transmit position, a regenerative connection is completed from the output electrodes of the tube 34e by way of the conductor 49e, the contacts 102e and 103e, the condenser 19e, and the shielded conductor 37e to the control grid electrode 35e of the amplifier tube 33e. When this regenerative connection is completed the audio amplifier 30e acts as an audio frequency oscillator and oscillates at approximately 400 cycles per second. The 400 cycle audio frequency generated by the amplifier 30e modulates the 60 kilocycle carrier wave generated by the oscillator 20e, and is transmitted in the previously described manner over the power line 10. Any other station of the system having its key, such as the key 5e, in its neutral or receive position will function in the manner previously described to control the sound translating device thereat to produce a 400 cycle tone signal. This signal will indicate to the operator thereat that another operator of the system is about to transmit printing telegraph coded signals.

In order to describe the manner in which the coded signals are scrambled during the operation of the transmitter 50e, it will be assumed that when the key 51e of the letter "C" is actuated, the code select bars 52e (II, III and IV) are marked to transmit the code signals of the letter "C." Consequently, when the arm 55e rotates in the direction indicated the contacts 56e (I and IV) are unmarked and the contacts 56e (II, III and V) are marked, due to the cross connections of the transposing plug 59e. As a result of the above described markings placed upon the contacts 56e of the transmitter 50e, the apparatus at the east station is controlled to transmit a carrier signal of 60 kilocycles which is modulated by a 400 cycle audio frequency at spaced intervals in accordance with the coded signals controlled by 75

the above mentioned marked contacts 56e (II, III and V). When these signals are received by the apparatus at the west station, the relay 61w thereat controls its associated contacts 65w to successively energize the contacts 64w (II, III and V). Thus, when the contact 65w (II) is energized, a circuit is completed by way of the BII terminal of the transposing plug 69w and the AII terminal thereof for energizing the relay 66w (II) of the printer 60w. When the 64w (III) terminal is energized, a circuit is completed by way of the BIII terminal of the transposing plug 69w and the BIV terminal thereof for energizing the relay 66w (IV). When the terminal 64w (V) is energized, a circuit is completed by way of the BV terminal of the transposing plug 69w and the AIII terminal thereof for energizing the relay 66w (III). As a result of the energization of the relays 66w (II, III and IV) the letter "C" is printed by the printer 60w.

It will be understood from the foregoing description of operation of the printer apparatus at the west station that if the transposing plug 69w had not been wired in the same manner as the transposing plug 59e at the east station, and had been wired straight, then the relays 66w (II, III and V) would have been energized to print a letter other than the letter "C," for example the letter "P." Since any number of transpositions may be made by providing a plurality of transposing plugs, each wired in a different manner, it will be understood that a transmitting station may, with the cooperation of a particular receiving station, determine the particular transposing plug to be utilized in the transmission of a particular message. If other stations of the system are unaware of the particular code wiring of the transposing plugs utilized in the transmission of the message, the printing apparatus at such stations will print a message which is undecipherable by the operator thereat, but at the receiving station which has the proper transposing plug connected to the printer apparatus, that is, a transposing plug corresponding in wiring to the transposing plug utilized by the transmitting station, the message recorded by the printer thereat will have been deciphered and correctly printed to correspond with the message transmitted.

While one embodiment of the invention has been disclosed, it will be understood that various modifications may be made therein which are within the true spirit and scope of the invention.

What is claimed is:

1. In combination with a printing telegraph station having a transmitter for transmitting a message by telegraphic coded signals and a receiver for printing a message transmitted by telegraphic coded signals from another station, a unit adapted to be operated as a carrier current oscillator or as a detector, means at said station for applying a predetermined positive voltage to said unit when said station is to be operated as a transmitting station thereby to control said unit to transmit a superaudio carrier frequency, means at said station for modulating said carrier frequency with an audio frequency in accordance with a telegraphic code to transmit a message, and means at said station for applying a predetermined lesser positive voltage to said unit when said station is to be operated as a receiving station thereby to control said unit to detect the audio portion of a telegraphically coded modulated carrier wave received at said station.

2. In combination with a printing telegraph station having a transmitter for transmitting a message by telegraphic coded signals and a re-

ceiver and a printer for receiving and printing a message transmitted by telegraphic coded signals from another station, a unit adapted to be operated as a carrier current oscillator or as a detector, means at said station for applying a predetermined positive voltage to said unit when said station is to be operated as a transmitting station thereby to control said unit to transmit a superaudio carrier frequency, means at said station for modulating said carrier frequency with an audio frequency in accordance with a telegraphic code to transmit a message, means at said station for applying a predetermined lesser positive voltage to said unit when said station is to be operated as a receiving station thereby to control said unit to detect the audio portion of a telegraphically coded modulated carrier wave received at said station, and means controlled in accordance with said detected signals for controlling said printer to make a record of the received message.

3. In a communication system, a line, a station connected to said line, said station comprising a first combination carrier current oscillator and detector device, a second combination audio frequency oscillator and amplifying device, a key controlled transmitter, and a printer; control means at said station actuated in one manner when said station is operated as a transmitting station for altering said first device to cause it to operate as a carrier current oscillator thereby to transmit carrier current oscillations over said line, means controlled by said transmitter for causing said second device to operate as an audio frequency oscillator thereby to modulate said carrier current oscillations in accordance with a telegraphic code, said control means actuated in another manner when said station is operated as a receiving station for altering said first device to cause it to operate as a detector thereby to demodulate received modulated carrier current oscillations and for causing said second device to operate as an amplifier thereby to amplify the said demodulated oscillations, and means controlled by said second device when operated as an amplifier for controlling said printer to produce a record of the letters or digits represented by the received demodulated oscillations.

4. In combination with a printing telegraph station having a transmitter for transmitting a message by telegraphic coded signals and a receiver for printing a message transmitted by telegraphic coded signals from another station, a carrier current oscillator, a combination audio frequency oscillator and amplifying device, a key controlled transmitter, a printer, a control key at said station actuated in one manner when said station is operated as a transmitting station for activating said carrier current oscillator to transmit a carrier wave, means controlled by said transmitter for causing said device to operate as an audio frequency oscillator thereby to modulate said carrier wave in accordance with a telegraphic code, said control key actuated in another manner when said station is operated as a receiving station for altering said carrier current oscillator to cause it to operate as a detector to demodulate received modulated carrier waves and for altering said device to cause it to operate as an amplifier thereby to amplify said demodulated carrier waves, and means controlled by said device when operated as an amplifier for controlling said printer to produce a record of the letters or digits represented by the received demodulated carrier waves.

5. In combination with a printing telegraph sta-

tion having a transmitter for transmitting a message by telegraphic coded signals and a receiver for printing a message transmitted by telegraphic coded signals over another station, a sound translating device, a unit adapted to be operated as a carrier current oscillator or a detector, means at said station for applying a predetermined positive voltage to said unit when said station is to be operated as a transmitting station thereby to control said unit to transmit a superaudio carrier frequency, means at said station for modulating said carrier frequency with an audio frequency in accordance with a telegraphic code to transmit a message, said last-mentioned means also controllable by said sound translating device for modulating said carrier frequency with an audio frequency in accordance with sound waves received by said sound translating device, means at said station for applying a predetermined lesser positive voltage to said unit when said station is to be operated as a receiving station thereby to control said unit to detect the audio portion of a modulated carrier wave received at said station, said amplifier amplifying said detected audio portion of a modulated carrier wave thereby to control said sound translating device to reproduce sound waves in accordance therewith and to cause said receiver to print a message in accordance with the audio portion of a telegraphically coded modulated carrier wave.

6. In combination with a printing telegraph station having a transmitter for transmitting a message by telegraphic coded signals and a receiver for printing a message transmitted by telegraphic coded signals from another station, a sound translating device, a first unit adapted to be operated as a carrier current oscillator or as a detector, a second unit including an input and an output circuit adapted to be operated as an audio frequency oscillator or as an amplifier, a switching key adapted to be actuated in a first manner to condition said station to be operated as a transmitting station and adapted to be operated in a second manner to condition said station to be operated as a receiving station, contacts controlled by said key when actuated in said first manner for controlling said first unit to operate as a carrier current oscillator to generate a carrier wave and for connecting said sound translating device to said input circuit whereby said second unit operates as an amplifier, means including said output circuit for modulating said carrier wave with amplified audio frequencies in accordance with sound waves received by said sound translating device and transmitted over said input circuit, means including the transmitter at said station for intermittently connecting said output circuit and said input circuit of said second unit in accordance with a telegraphic code thereby to cause said second unit to modulate said carrier wave with a telegraphically coded predetermined audio frequency, contacts controlled by said key when actuated in said second manner for controlling said first unit to operate as a detector thereby to detect the audio portion of a modulated carrier wave received at said station and for connecting said sound translating device to said output circuit and connecting said input circuit to said detector whereby the detected audio portion of said modulated carrier wave is amplified by said second unit and reproduced as sound waves by said sound translating device, and means for coupling the receiver at said station to said output circuit in order to print a message in accordance with the detected audio

portion of a telegraphically coded modulated carrier wave.

7. In combination with a printing telegraph station having a transmitter for transmitting a message by telegraphic coded signals, a sound translating device, a first unit adapted to generate a carrier wave, a second unit including an input and an output circuit adapted to be operated as an audio frequency oscillator or as an amplifier, a switching key, contacts controlled by said key for controlling said first unit to generate said carrier wave and for connecting said sound translating device to said input circuit thereby to condition said second unit to operate as an amplifier, means including said output circuit for modulating said carrier wave with amplified audio frequencies in accordance with sound waves received by said device and transmitted over said input circuit, and means including the transmitter at said station for intermittently interconnecting said output and said input circuits in accordance with a telegraphic code to cause said second unit to operate

5

as an audio frequency oscillator whereby said carrier wave is modulated in accordance with a telegraphically coded predetermined audio frequency.
